UNITED STATES PATENT OFFICE.

RICHARD HERVIG, OF CHICAGO, ILLINOIS, ASSIGNOR TO AMERICAN CAR AND FOUNDRY COMPANY, OF NEW YORK, N. Y., A CORPORATION OF NEW JERSEY.

DRILL-TWISTING MACHINE.

1,405,414.

Specification of Letters Patent. Patented Feb. 7, 1922.

Application filed June 10, 1920. Serial No. 388,050.

To all whom it may concern:

Be it known that I, RICHARD HERVIG, residing at Chicago, county of Cook, State of Illinois, and being a citizen of the United States, have invented certain new and useful Improvements in Drill-Twisting Machines, of which the following is a full, clear, and exact description, such as will enable others skilled in the art to which it applies to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Figure 1 is a view partly in elevation and partly in section of my improved machine;

Figure 2 is an end elevation, looking from the left in Fig. 1;

25 Figure 3 is a section through the sleeve carriage and sleeve, showing a twisted blank in position in the sleeve;

Figure 4 is a view in plan of a loose collar or sleeve used in determining the degree of twist given to the blank;

30 Figure 5 is a sectional view taken on the line 5—5 of Fig. 1 showing the blank positioned with respect to the adjustable holding means in the sleeve; and

Figure 6 is a view showing the use of a plurality of the sleeves shown in Fig. 4 where it is desired to give a greater amount of twist to a blank or to twist a longer blank.

It is the object of my invention to provide an improved machine for twisting drill blanks of such structure that it may be quickly adjusted to give the desired degree of twist to a blank or to operate upon blanks of different lengths.

The machine comprises a bed or base plate 1 carried upon a suitable support 2. At one end, the base plate 1 is provided with integral uprights or standards 3 and 4 that carry an integral split head 5 having the lugs 6 in which are the screws 7. The base plate 1 also has a raised flat portion 8 provided with under-cut guides 9 and 10 (shown dotted in Fig. 2) engaged by the base of the sleeve carriage 11. Secured to

one side of the base plate 1, by screws 12, is a rack bar 13, while to the other side of the base plate 1 the ratchet bar 14 is secured by screws 15. Engaging with the rack bar 13 and serving to operate the sleeve carriage 11 on its guides is a gear wheel 16 operated by a hand wheel 17 and carried by a pivot pin fixed in a projection 18 integral with the sleeve carriage 11. Mounted upon pins 19 and 20, screwed into lugs upon the opposite side of the sleeve carriage, are the pawls 21 and 22, adapted to engage the ratchet bar 14, the pawls 21 and 22 being so spaced with respect to the teeth on the ratchet bar 14 that when one pawl is engaged with a ratchet tooth the other pawl rests upon the inclined face of a ratchet tooth, midway of its length, thus making it possible to give the sleeve carriage positions differing by only one half the length of a ratchet tooth. The upper ends of the pawls 21 and 22 are connected by the link 23 which is pivotally connected to each pawl, as by pin 24. Perpendicular to the link 23 at its center is a tapered member 25 having a spherical end piece 26 which serves as a convenient handle to be grasped by the operator when it is desired to operate the pawl and as a weight for holding the pawls in engagement with the ratchet bar or out of engagement therewith.

Inserted in a longitudinal bore in the sleeve carriage 11 is the blank carrying sleeve 27 having a central bore closed at one end by a screw threaded plug 28 and screws 29 which project into the bore from opposite sides of the sleeve 27 and serve to prevent rotation of the blank 30 in the sleeve 27. The sleeve 27 is also provided with an integral collar 31 which serves to position the sleeve in the opening in the sleeve carriage 11, the collar 31 having a flat portion 32 adapted to engage a flat portion 33 on the sleeve carriage 11 and prevent the sleeve 27 from being rotated in the bore in the sleeve carriage 11. A screw 33 in opening 34 in the sleeve carriage 11 engages in a notch 35 in the sleeve 27 and prevents the withdrawal or movement of the sleeve 27.

In the head 5 is mounted a spindle 36 provided with a central longitudinal bore and having a chuck 37 secured to its inner end to serve as a driving means for the

blanks and a collar 48 fitted in the bore to carry the end of the blank. A collar 38, integral with the spindle 36, engages the face of the head 5 and positions the spindle 5 in the head while fitted in the bore in the spindle 36 is an ejector rod 39 adapted to slide in the bore and to engage the end of the blank to aid in freeing the blank. Mounted upon the spindle 36 so as to turn 10 freely thereon is a collar 40 having a projection 41 adapted to engage a pin 42 inserted in one of a plurality of openings 43 in the face of the standard 3. As shown in Fig. 6, a plurality of collars 40 may be 15 used in place of a single collar where it is desired to give a greater amount of twist to the blank or to twist a longer blank, the projection 41 on each of the additional collars 40 engaging the projection 41 on the 20 next collar toward the standard. Keyed to the spindle 36 is a crank 44 having a handle (not shown) and provided with a projection 45 adapted to engage the projection 41 on the adjacent collar 40. Screwed 25 on the spindle 36 and held in position by set screws 46 are the locking collar 47 and cap 49 that serve to keep the crank 44 and loose collars 40 close together so that the pin 42 and the various projections 41 on the collars 40 will be engaged. This arrangement, when the handle has been turned 30 to its limit, permits the handle to have a predetermined movement before it engages the projection 41 on the adjacent collar 35 40. The collar will then move with the handle until, in case but one collar is used, the projection 41 engages the pin 42. Where more than one collar is used, the projections 41 are successively engaged and the corresponding collars moved with the handle 40 until the projection 41 on the collar adjacent the head 5 engages the pin 42. The number 45 of collars 40 and the position of the pin 42 in the series of openings 43 determines the extent of the movement of the handle. As this operation takes place irrespective of the direction in which the handle 44 is turned, the handle and spindle are turned through 50 a definite arc each time the handle is operated between its extreme positions and this amount may be varied to suit the requirements in the case of any particular blank by changing pin 42 from one opening 43 to another and by varying the number of 55 the collars 40 on the spindle 36.

In operation, the pawls are operated by the handle 26 permitting the sleeve carriage 11 and the sleeve 27 to be drawn away from the chuck 37 by the operation of the 60 hand wheel 17 so that a blank 30 may be inserted in the sleeve. The blank, properly heated, being inserted in the sleeve 27 with the end of the blank between the screws 29 and bearing against the plug 28, the hand wheel 17 is operated to bring the sleeve

carriage 11 towards the chuck 37 so that the shank end of the blank may be engaged by the chuck 37 and the end of the blank engage the collar 48. Operating the handle 44 from one extreme position to the other will give the blank the desired amount of twist, after which the chuck 37 is opened, the pawls 21 and 22 lifted, and the hand wheel 17 operated to withdraw the blank from the chuck 37. The handle 44 is then 75 returned to its other extreme position.

What I claim is:

1. In a drill twisting machine, a base plate, a sleeve carriage adjustable on said base plate, a blank carrying sleeve carried by said carriage, means carried by said sleeve to hold the blank against rotation, a head carried by said base plate, a spindle in said head, means for rotating said spindle in said head and adjustable means on said head and co-operating means on said spindle for determining the degree of rotation of said spindle.

2. In a drill twisting machine, a base plate, a sleeve carriage adjustable on said base plate, a blank carrying sleeve carried by said carriage, a head carried by said base plate, a spindle carried by said head, a pin carried by said base plate, a collar on said spindle adapted to engage said pin and means to rotate said spindle adapted to engage said 95 collar.

3. In a drill twisting machine, a base plate, a sleeve carriage adjustable on said base plate, a blank carrying sleeve mounted in said sleeve carriage and adapted to hold a blank against rotation with respect to said sleeve carriage, a head carried by said base plate, a spindle in said head adapted to rotate a blank with respect to said sleeve carriage, means for rotating said spindle and adjustable means on said head for limiting the amount of such rotation.

4. In a drill twisting machine, a base plate, a sleeve carriage adjustable on said base plate, a blank carrying sleeve mounted in said sleeve carriage and held against rotation therein, a head mounted on said base plate, a spindle in said head adapted to co-operate with said sleeve in twisting a blank, a pin adjustably positioned in said head, a collar rotatable on said spindle and adapted to engage said pin and a crank handle mounted on said spindle and adapted to engage said collar and limited in its movement by the engagement of said handle, said collar and 120 said pin.

5. In a drill twisting machine, a base plate, means carried by said base plate adapted to hold a blank against rotation, a head carried by said base plate, a spindle mounted in said head and adapted to rotate the blanks, a pin adjustably mounted in said head, a collar loosely mounted on said spindle and adapted to engage said pin, a crank handle keyed to said spindle, adapted to engage said 130

collar and limited in its movement in both directions by the engagement of said handle, said collar and said pin.

6. In a drill twisting machine, a base plate, means adjustable on said base plate adapted to hold a blank against rotation, means for adjusting said blank holding means on said base plate, means for securing said blank holding means against movement in one direction while permitting movement in the opposite direction and means carried by said base plate for rotating the blank.

7. In a drill twisting machine, a base plate, means adjustable on said base plate adapted to hold a blank against rotation, gearing carried by said means and said base plate for adjusting said means on said base plate, a pawl and ratchet for preventing movement of said means in one direction and means, carried by said base plate and having a limited movement in opposite directions, for rotating said blank.

8. In a drill twisting machine, a base plate, means carried by said base plate adapted to hold a blank against rotation, a head carried by said base plate, a hollow spindle mounted in said head and adapted to rotate the blank, operating means for said spindle, means carried by said operating means, said spindle

and said head for limiting the movement of 30 said spindle and an ejector rod for the blank mounted in said spindle.

9. In a drill twisting machine, a base plate, a sleeve carriage, holding means for said carriage adapted to permit movement 35 of said carriage in one direction, a blank carrying sleeve carried by said carriage, a head carried by said base plate, a spindle in said head adapted to rotate the blank, means for rotating the spindle and adjustable 40 means on said head for limiting the rotation of said spindle in both directions.

10. In a drill twisting machine, a base plate, a sleeve carriage freely movable in one direction on said base plate, a blank 45 carrying sleeve mounted on said carriage, means carried by said sleeve to prevent rotation of the blank, a head carried by said base plate, means carried by said head adapted to rotate said blank and adjustable 50 means carried by said head and adapted to limit the rotation of the blank.

In witness whereof I have hereunto set my hand in the presence of two witnesses.

RICHARD HERVIG.
